UNITED STATES PATENT OFFICE.

VERNER RUSSELL CHADWICK, OF LONDON, ENGLAND.

FURNACE.

Application filed March 27, 1923. Serial No. 628,094.

To all whom it may concern:

Be it known that I, VERNER RUSSELL CHADWICK, a subject of the King of England, residing at London, England, have invented certain new and useful Improvements in Furnaces, of which the following is a specification.

This invention is for improvements in or relating to furnaces, and has for its object to provide an improved construction of the same which, whilst offering advantages for the combustion of any kind of fuel over types of furnace hitherto known, is particularly suitable for burning powdered coal, such as anthracite dust. It has not hitherto been practicable to burn fuel such as this, so that it has been a waste product, but by means of the construction hereinafter described, it is possible effectively to utilize all such fuel.

Amongst other advantages it may be stated that in furnaces of the type in which air is delivered under forced draught by steam injection or otherwise, it has been difficult to obtain a uniform rate of combustion over the whole grate area. This difficulty is overcome by the present invention, and the resulting uniform rate of combustion over the whole surface of the fire-bars effects an economy by ensuring a more complete consumption of the smoke and other products of combustion; another advantage is that the fire-bars as hereinafter described are individually removable or replaceable.

This invention comprises a furnace-grate for burning coal-dust and like materials wherein the air for combustion is delivered through the fuel-supporting-surface by means of a plurality of openings distributed over the surface, the channels communicating with said openings being inclined to the fuel-supporting-surface at a small angle; such that the fuel, even although in the form of powder, will not slide down the channels and by blocking them prevent the supply of air for combustion.

According to another feature of this invention, a furnace-grate for burning coal-dust and like materials comprises a plurality of transverse fire-bars arranged near one another to receive the fuel on their upper surfaces, but spaced apart to provide an air-passage, and opening, along the opposite edges of the upper surface of each bar, each of said bars being formed with a plurality of channels whereof each communicates at one end with one of said air-passages, and is

open at its other end to the said upper surface of the bar at a point spaced away from the edge of the bar, and means for directing the flow of air along said channels. 60

According to another feature of this invention, the channels aforesaid take the form of grooves extending along the upper surface of the bar from an edge thereof, and projections are formed on each fire-bar to 65 co-operate with the said grooves of an adjacent bar to direct the air-flow therealong.

Other features of the invention are hereinafter described with reference to the specific constructions illustrated in the accompanying drawings, and the novel details are set forth in the claims appended to this specification. 70

In the accompanying drawings—

Figure 1 is a broken plan view showing two fire-bars in accordance with this invention; 75

Figure 2 is a front elevation of Figure 1; Figure 3 is a section on the line 3—3 of Figure 2; 80

Figure 4 is a broken plan showing a modified construction of fire-bar;

Figure 5 is a vertical section on the line 5—5 of Figure 4; 85

Figure 6 is a longitudinal section showing the application of this invention to an internally-fired boiler;

Figure 7 is a similar view of an externally-fired boiler; and 90

Figure 8 is a partial section on the line 8—8 of Figure 3. 95

Like reference characters indicate like parts throughout the drawings.

Referring first to Figures 1, 2 and 3, each fire-bar comprises end portions 10 which are substantially rectangular, and which engage the supports for the bars. The parts of the bar between the ends 10 are of substantially triangular section, as shown at 11, the triangles being preferably inclined downwardly and forwardly towards the front of the furnace, or opposed to the flow of air entering the furnace, and they are so dimensioned that when the bars are assembled one behind the other, with the portions 10 abutting, a channel 12 is provided between the parts 11 of the fire-bars, this channel tapering upwards, as shown in Figure 3, and terminating in a narrow slot 13, (see Figure 1) in the surface which supports the fuel. 105

In order to provide for a more wide-

spread distribution of the air, the fire-bars are formed, according to this invention, with channels or grooves 14 extending from the air-passage aforesaid along the upper surface 5 of the bars, as shown most clearly in Figures 1 and 3. The bottom 15 of the groove is inclined at only a small angle to the upper surface 16 of the fire-bar whereon the fuel rests, this angle being less than the angle of 10 repose of the fuel on the grate so that the fuel will not slide down it and choke the channel or fall through into the ash-pit. The bottom 17 of the lower part of the groove 14 is sloped at a greater angle to the 15 surface 16 aforesaid in order to provide an adequate cross-sectional area for the admission of the air, and also to accommodate a projection 18 which is formed on an adjacent bar and which serves to divert some of 20 the air passing up the passage 12 along the groove 14. Each fire-bar is provided with a number of these grooves 14 which are made of such a length and are spaced apart by such a distance as to ensure that the air is 25 distributed substantially uniformly throughout the whole layer of fuel on the fire-bars. The air flows up these grooves in a practically straight line so that air-friction losses and eddies therein are avoided.

30 Another feature of construction of the fire-bars as above described consists in the provision in each bar of a lug 19 extending laterally from the portion 11 of the bar in such a position that it extends 35 through a slot 20 on the adjacent fire-bar and lies near the corresponding lug 19 on the said adjacent fire-bar. In this way, an interlocking of the bars with one another is effected, so that there is no risk of a bar rising 40 or being forced upwards by expansion when in use.

In Figures 4 and 5 there is illustrated a modified formation of fire-bars in which the 45 portions of the bars between the ends are of waved formation instead of being substantially rectangular, as shown in Figure 1. The ends 10 of these modified bars are conveniently rectangular, and the intermediate 50 portions 21 are so shaped as to provide a waved slot 22 corresponding to the slot 13 illustrated in Figure 1. The intermediate parts 21 of these bars may be arranged as shown in Figure 5 substantially at right-angles to the fuel-supporting-surface 23, and 55 when this construction is used, the channels 24, which correspond to the channels 14 of the construction first described, may be arranged to extend from both edges of a bar towards the other edge thereof, and the co-operating projections 25 on the adjacent fire-bars are provided in the same manner to 60 direct the air-flow along the channels or grooves 24. Conveniently the channels 24 in each bar extend along the surface of the bar from a convex edge of the waved slot 22,

and accordingly, the co-operating projections 25 extend from a concavely-curved edge of the slot 22, as shown most clearly in Figure 4.

In Figure 6 there is illustrated the application of this invention to an internally-fired forced-draught boiler. The furnace-flue is indicated by the reference 26, and there is provided within the furnace a plurality of trough-shaped members 27 which 70 diminish in cross-section from the front ends 28 towards the rear ends 29. The upper open sides of these troughs are occupied by a series of fire-bars constructed as hereinbefore described, these bars being illustrated 75 more or less diagrammatically and indicated by the reference character 30. The air for combustion is supplied under pressure in any ordinary or desired manner from the front of the furnace 31, the usual fittings 80 and appliances being provided, such for example, as the air-moistening device 32.

Figure 7 illustrates the application of this invention to an externally-fired boiler. In this case the air for combustion of the fuel 90 may be supplied by steam air-injectors 33, 34, to a plurality of trough-shaped members 35 carrying the fire-bars 36 whereon the fuel is burnt. The trough-shaped members 35 are, as before, preferably tapered from the 95 front end to the rear end so as to ensure a uniform distribution of air as between the back and front of the furnace and the fire-bars 36 are of the type illustrated in Figures 1, 2 and 3, of substantially triangular section 100 directed downwardly and forwardly against the flow of the entering air.

This invention provides a construction of furnace which ensures that the air for combustion is distributed uniformly over the 105 whole grate area, and one, moreover, in which the air is supplied through a very large number of small channels so that the uniformity of distribution is practically independent of the nature of the fuel which 110 is being burnt; it is thereby rendered possible to burn powdered noncoking fuels, such for example as anthracite dust, and other materials which it has not been possible to use hitherto. Also the construction and 115 arrangement of the furnace is extremely economical in first cost and in repairs and maintenance.

What I claim as my invention and desire 120 to secure by Letters Patent is:

1. A furnace-grate for burning coal-dust and other pulverized material, comprising a plurality of fire-bars arranged side-by-side near one another to receive fuel on their upper surfaces, which bars have their fuel-bearing portions spaced apart to provide air gaps between them and are cast each with a plurality of air-supply channels which are directed upwards along their entire length and open upwards each 125

- through an air opening at an edge of the upper surface of each bar, which channels have their upper parts situated each in one bar and open downwards into one of said air gaps, and the top portion of each said channel is sloped downwards at an angle less than the angle of repose of the fuel on the bars so that fuel will not slide down the said channels, which bars are further cast each with a plurality of projections on one side thereof arranged to extend each into said channel in an adjacent bar for directing the air flow along the same.
2. A furnace-grate for burning coal-dust and other pulverized material, comprising a plurality of fire-bars arranged side-by-side near one another to receive fuel on their upper surfaces, which bars have their fuel-bearing portions spaced apart to provide air gaps between them and are cast each with a plurality of air supply channels which are directed upwards along their entire length and open upwards each through an air opening at an edge of the upper surface of each bar, which channels have their upper parts situated each in one bar and open downwards into one of said air gaps, the top portion of each said channel is sloped downwards at an angle less than the angle of repose of the fuel on the bars, and the next lower portion of each channel slopes downwards at a greater angle than the angle of slope of the top portion, which bars are further cast each with a plurality of projections on one side thereof arranged to enter into the channels in an adjacent bar at the bottom of said top portion where the change in slope of the channel occurs.
3. A furnace-grate for burning coal-dust and other pulverized material, a fire-bar formed with a flat upper surface to receive the fuel, with spacing means to provide an air space along one edge of said upper surface, and with a plurality of channels communicating each with one of said air spaces and extending each as a transverse open groove in the said upper surface from the said edge thereof, the bottoms of which grooves slope downwards each at an angle less than the angle of repose of the fuel on the bars, and projections extending from the opposite edge thereof to cooperate with the channels of an adjacent fire bar.
4. For a furnace-grate for burning coal-dust and other pulverized material, a fire-bar formed with a flat upper surface to receive the fuel, with spacing means to provide an air space along one edge of said upper surface, and with a plurality of channels communicating each with one of said air spaces and extending each as a transverse open groove in the said upper surface from the said edge thereof, the bottoms of which grooves slope downwards each at an angle less than the angle of repose of the fuel on the bars, and projections extending from the opposite edge thereof to cooperate with the channels of an adjacent fire bar.

In testimony whereof I affix my signature.
VERNER RUSSELL CHADWICK.
